UNITED STATES PATENT OFFICE.

HAROLD ALFRED ROGERS, OF CARDIFF, WALES.

SOUND RECORDING AND REPRODUCING MACHINE.

Application filed September 19, 1924. Serial No. 738,625.

To all whom it may concern:

Be it known that I, HAROLD ALFRED ROGERS, a subject of the King of Great Britain and Ireland, of 56 New Zealand Road, 5 Cardiff, Wales, have invented certain new and useful Improvements in or Relating to Sound Recording and Reproducing Machines, of which the following is a specification.

10 This invention relates to improvements in or relating to sound recording and reproducing machines and in particular to improved means for controlling the speed of the turntable so that when desired the turntable may 15 be caused or allowed to run at an increasing angular speed as the needle passes across the record from the outside towards the centre.

In previously known constructions directed to this object it has been proposed to use a motor running at a constant angular speed but with a variable transmission between the motor and the turntable. In some cases the motor drives at a constant angular 25 speed a friction pulley which passes across the turntable or across a separate disc on the turntable spindle. In other known constructions it has been proposed to have a speed control friction wheel running on the 30 turntable or on the record and in gear with a governor which allows the control wheel to run only at a constant angular speed. As this control wheel passes across the record towards the centre of the turntable it allows the turntable and consequently the motor to 35 increase its angular speed of rotation.

According to the present invention a speed control wheel connected with the governor which allows it to run at a constant angular 40 speed is mounted to co-operate with a separate friction disc geared to the motor or turntable spindle and this control wheel is caused to travel across the friction disc by being suitably connected with a travelling 45 part of the machine such as the sound arm. The friction disc being geared with the motor, the variation in speed of the friction disc permitted by the travelling control 50 wheel causes a proportionate variation in speed of the turntable.

The invention is illustrated in the accompanying drawings in which—

Fig. 1 is an underside plan view of a 55 spring motor to which the present invention is applied,

Fig. 2 is a side elevation of the same,

Fig. 3 is a side elevation at right angles to Fig. 2,

Fig. 4 is a side view on an enlarged scale of the governor and the preferred form of 60 mounting.

Referring to Figs. 1, 2 and 3, the spring drum 26 carries a gear wheel 28 engaging with a worm on the turntable spindle 24 carrying the turntable 27. Mounted on the 65 spindle 24 is a worm wheel 29 which drives the shaft 30 carrying a friction disc 25. The friction disc 25 and the spindle 30 occupy the position usually occupied by the governor and governor spindle of a talking machine motor. The disc 25 is preferably faced with leather or other suitable non-slipping material.

The speed control device consists of a control wheel 18 rotatably mounted on a rod 33 75 which passes through the arms of a carriage 33' carrying the governor spindle 31, to which the control wheel 18 is geared by means of a worm on the spindle and deeply cut teeth on the wheel 18, said carriage being supported upon a track 49. The speed of the centrifugal governor is determined in the usual manner by means of a friction pad 80 engaging with a friction disc mounted on the sliding collar 38 of the governor. 85

The rod 33 is connected to the sound arm for example, of the talking machine by means of a shaft 46 having gears at its ends, one meshing with the teeth of a sector 47 moving with said sound arm, and the other meshing with teeth on a rack 48 formed at the end of said rod. The object of this connection is to cause the rod 33 to be moved end-ways as the sound arm moves across the record with the result that the control wheel 18 moves across the disc 25 thus allowing the disc 25 and consequently the motor to increase its angular speed. It is apparent that the connecting means here shown and described for transmitting motion from the sound arm to the rod 33 are merely illustrative of any of a range of well known mechanical equivalents which may be utilized for this purpose.

As shown in Fig. 4 the governor spindle 31 is preferably mounted at either end in self-aligning ball bearings carried by the governor carriage. Between the fixed collar 37 and the sliding collar 38 are fixed 105 spring blades which carry weights 32 in the form of discs lying substantially at right angles to the blades. The spring blades 110

pass through slots 39 in the friction disc attached to the sliding collar 38. The rim of the control wheel 18 is of metal preferably steel or brass with a tyre of fibre, rubber or other gripping or non-slipping material wherein the teeth for engaging with the worm 35 are deeply cut.

I claim:

1. In a sound recording or reproducing machine, a turntable, a motor for operating the same, a sound arm movable from the peripheral portion of said turntable toward the center thereof by co-action with a record, means for varying the angular speed of rotation of the turntable comprising a friction disk positively driven by the motor, a governor, a speed control wheel operatively connected to said governor and governed thereby, and means operated by the movement of the sound arm across the record for producing a rectilinear movement of said

control wheel across the face of said friction disk.

2. In a sound recording or reproducing machine, a turntable, a motor for operating the same, a sound arm movable from the peripheral portion of said turntable toward the center thereof by co-action with a record, means for varying the angular speed of rotation of the turntable comprising a friction disk positively driven by the motor, a governor, a speed control wheel operatively connected to said governor and governed thereby, and rectilinearly movable means responsive to movement of the sound arm across the record for moving said control wheel across the face of said friction disk, said governor being carried by and movable with said means.

In testimony whereof I have signed my name to this specification.

HAROLD ALFRED ROGERS.
